US0D1013679S

(12) **United States Design Patent** (10) Patent No.: **US D1,013,679 S**
(45) Date of Patent: ** Feb. 6, 2024

(54) **LAPTOP COMPUTER**

(71) Applicant: **Lenovo (Beijing) Limited**, Beijing (CN)

(72) Inventors: **Chih-kai Huang**, Beijing (CN); **Runsheng Liang**, Beijing (CN)

(73) Assignee: **Lenovo (Beijing) Limited**, Beijing (CN)

(**) Term: **15 Years**

(21) Appl. No.: **35/515,923**

(22) Filed: **Oct. 26, 2022**

(80) **Hague Agreement Data**

Int. Filing Date: **Oct. 26, 2022**

Int. Reg. No.: **DM/225678**

Int. Reg. Date: **Oct. 26, 2022**

Int. Reg. Pub. Date: **Dec. 30, 2022**

(30) **Foreign Application Priority Data**

Apr. 26, 2022 (CN) 202230240457.5

(51) **LOC (14) Cl.** **14-02**

CLAIM

The ornamental design for a laptop computer, as shown and described.

DESCRIPTION

1. Laptop computer

1.1 : Front

1.2 : Back

1.3 : Left

1.4 : Right

1.5 : Top

1.6 : Bottom

1.7 : Perspective

1.8 : Perspective view of the laptop computer in an opened state

(Continued)

The broken lines shown in the drawings illustrate portions of the laptop computer that form no part of the claimed design.

1 Claim, 8 Drawing Sheets
